US0D1082925S

(12) **United States Design Patent** (10) **Patent No.:** **US D1,082,925 S**
(45) **Date of Patent:** **** Jul. 8, 2025**

(54) **TAPE FEEDER**

- (71) Applicant: **Panasonic Intellectual Property Management Co., Ltd.**, Osaka (JP)
- (72) Inventors: **Yoshinori Isobata**, Fukuoka ken (JP); **Minoru Kitani**, Fukuoka ken (JP); **Satoshi Kawaguchi**, Fukuoka ken (JP); **Kyourei Ri**, Fukuoka ken (JP); **Atsuyuki Horie**, Fukuoka ken (JP); **Hiroaki Kato**, Fukuoka ken (JP); **Chikara Takata**, Fukuoka ken (JP); **Tatsuo Yamamura**, Fukuoka ken (JP); **Kunimi Tsuzurugi**, Fukuoka ken (JP)
- (73) Assignee: **Panasonic Intellectual Property Management Co., Ltd.**, Osaka (JP)
- (**) Term: **15 Years**
- (21) Appl. No.: **29/838,598**
- (22) Filed: **May 13, 2022**

CLAIM

The ornamental design for a tape feeder, as shown and described.

DESCRIPTION

FIG. 1 is a first perspective view of a tape feeder, showing our new design;

FIG. 2 is a second perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

1 Claim, 8 Drawing Sheets
